• *Black and white.*

Atty.

UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

TOOL MOUNTING.

Application filed July 6, 1920. Serial No. 394,319.

To all whom it may concern:

Be it known that I, ELMER G. GARTIN, a citizen of the United States, residing at Claremont, in the county of Sullivan and State of New Hampshire, have invented certain new and useful Improvements in Tool Mountings, of which the following is a full, clear, and exact specification.

My invention relates to tool mountings and more especially to adjustable mountings for pneumatic tools adapted to rock drilling purposes.

An object of my invention is to provide an improved tool mounting. Another object of my invention is to provide an improved mounting for rock drilling devices. A further object of my invention is to provide an improved mounting for rock drilling devices which is readily adjustable to accommodate devices of different size. A still further object of my invention is to provide an improved mounting for rock drilling devices which will accommodate a plurality of different sizes of devices and by means of which the devices may be adjusted toward or from the work.

In the accompanying drawings I have shown for purposes of illustration, one embodiment which my invention may assume in practice.

In these drawings,—

Fig. 1 is a view partially in elevation and partially in central longitudinal vertical section taken through the illustrative embodiment of my tool mounting showing a tool mounted therein.

Figs. 2 and 3 are transverse sections, on the lines 2—2 and 3—3, respectively, of Fig. 1, of the mounting.

For purposes of illustration I have disclosed the illustrative embodiment of my improved tool mounting in connection with a percussive motor 1 having a handle secured thereto and indicated by 2 and having a portion 3 formed for cooperation with a suitable clamp. This rock drilling tool is mounted on a cradle 4 which is provided adjacent its opposite ends with slides 5 and 6 in which cross heads 7 and 8 are slidably mounted. The cross head 7 is provided with a clamp generally indicated by 9 secured thereto and comprising a fixed jaw 10 and a movable jaw 11 pivoted to the jaw 10 as at 12. These jaws are controlled by means of a nut 13, having a controlling handle 14,

and a bolt 15, the bolt passing through both members of the clamp and the tool having the cylinder portion thereof clamped by the clamp members at the neighborhood of the portion 3 which is especially shaped for the purpose. The rear cross head 8 is provided with a socket 16 and a cover 17 therefor to receive the tool handle 2, the cover being pivotally mounted on a stud 18 and being adapted to be held in fixed position by means of a nut 19 and a second stud 20. For the purpose of providing a slight flexibility and also for the purpose of avoiding vibration, a shock absorbing spring 21 is secured to the cross head 8 by means of the stud 18 and is also secured to the end of a mounting 22 formed integral with the cradle 4 by means of a second stud 23, washer 24, and nut 25. A suitable nut 26 of well known construction is secured to the cradle 4 and cooperates with a feed screw 27 mounted in a shell 28 in which the cradle as a whole is slidable. By reason of the slidable mounting of the cross head 7 in the guides 5, drills of different lengths may obviously be employed in a single size of cradle and accordingly a device, capable of wide use, is produced in that but one model needs to be made for a plurality of different sizes of drilling implements.

From the foregoing description it will be seen that I have provided a simple, readily adjustable, universal tool mounting for use in connection with ordinary pneumatic tools of the hand type.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. A tool mounting comprising a cradle member, longitudinally separated clamping means adapted to grip a tool carried thereby, and means whereby the distance between said clamping means may be varied.

2. A tool mounting comprising a cradle member, longitudinally separated clamping means adapted to grip a tool carried thereby, and means whereby the distance between

said clamping means may be varied to accommodate tools of different lengths.

3. A tool mounting comprising a cradle member, longitudinally separated clamping means carried thereby, one of which is adapted to grip a tool, and means whereby the distance between said clamping means may be varied to accommodate unitary tools of different lengths.

10 4. A tool mounting comprising a cradle member, longitudinally separated clamping means adapted to grip a tool carried thereby, and means whereby one of said clamping means may be adjusted relative to the other to accommodate unitary tools of different lengths.

5 5. In a tool mounting, the combination comprising a cradle member, a tool supported thereby and slideable relative thereto, and 20 a resilient shock absorbing connection between said cradle member and said tool.

25 6. A tool mounting comprising a cradle member, longitudinally separated clamping means to grip the forward and rear ends of 25 a tool carried thereby, and means whereby the forward clamping means may be adjusted relative to the rear clamping means to accommodate unitary tools of different lengths.

30 7. A tool mounting comprising a cradle member, clamping means for a tool mounted thereon, slideable mountings for said clamping means, and a spring extending between one of said mountings and a fixed part of 35 said cradle.

35 8. In a tool mounting, the combination comprising a shell, a cradle slideably mounted therein, parallel guides on said cradle, a plurality of cross heads slideable in said 40 guides and means for securing a tool to said cross heads.

45 9. In a tool mounting, the combination comprising a shell, a cradle slideably mounted therein, parallel guides on said cradle, a plurality of cross heads slideable in said 45 guides, and means for securing a tool to said cross heads and for flexibly connecting one of said cross heads to the cradle.

50 10. A tool mounting comprising a shell, a cradle member movable longitudinally thereof, means slideable in said cradle member constituting tool clamping and supporting means, and means for resiliently connecting said slideable means and a tool carried thereby to said cradle member.

55 11. In a tool feeding mechanism, a movable carriage, means for moving the latter toward the work, and means for attaching a hand portable fluid pressure rock drill to 60 said carriage including a pair of tool clamping devices each longitudinally movable relative to said carriage and means for limiting the range of movement thereof.

12. In a tool feeding mechanism, a movable carriage, means for moving the same toward the work, means slideably mounted on said carriage for wholly supporting and gripping a tool, and a resilient connection extending between a portion of said last mentioned means and said carriage. 65

70 13. A tool mounting comprising a shell, a cradle slideably mounted thereon, means for feeding said cradle relative to said shell, guides formed in said cradle, crossheads slideably mounted in said guides, and means carried by said crossheads for clamping a unitary tool in operative position thereon. 75

80 14. A tool mounting comprising a shell, a cradle slideably mounted thereon, means to feed said cradle relative to said shell, guides formed in said cradle, crossheads slideably mounted in said guides, means carried by said crossheads for clamping a unitary percussive tool in operative position thereon, and a resilient connection between one of 85 said crossheads and said cradle.

90 15. A tool mounting comprising a tool, a cradle slideably mounted thereon, means for feeding said cradle relative to said shell including a feed nut carried by said cradle and a cooperating feed screw, guides formed in said cradle, crossheads slideably mounted in said guides, and means carried by said crossheads for clamping a unitary percussive tool in operative position thereon. 95

16. A tool mounting comprising a shell, a cradle adjustable relative thereto, a plurality of clamping members slideably mounted on said cradle adapted to clamp a unitary tool in operative position thereon, and a shock absorbing connection disposed between said cradle and one of said clamping members. 100

105 17. A tool mounting comprising a cradle member, longitudinally separated slideable clamping means carried thereby adapted to clamp a unitary tool in operative position thereon, and means whereby the distance between said clamping means may be varied to accommodate unitary tools of different 110 lengths.

115 18. A tool comprising a cradle member, longitudinally separated slideably mounted clamping means adapted to grip a unitary tool carried thereby, and means whereby the distance between said clamping means may be varied.

120 19. In a tool mounting adapted to support a motor, the combination comprising a shell, a cradle slideably mounted therein, parallel guides on said cradle, a crosshead to receive said motor and slideable in said guides, and means for securing said motor in operative relation to said crosshead.

In testimony whereof I affix my signature.
ELMER G. GARTIN.
